[57] CLAIM

The ornamental design for player restraint and gun
mount for amusement ride, as shown and described.

DESCRIPTION

FIG. 1 is a perspective view of a player restraint and
gun mount for amusement ride showing my new design;
FIG. 2 is a left side view thereof, it being understood
that the right side view is identical to that of FIG. 2.
FIG. 3 is a front view thereof;
FIG. 4 is a rear view thereof;
FIG. 5 is a top plan view thereof; and
FIG. 6 is a bottom view thereof.
